UNITED STATES PATENT OFFICE.

GEORGE R. PERRY, OF BROOKLYN, NEW YORK.

DISK OR COIN HOLDER.

SPECIFICATION forming part of Letters Patent No. 685,526, dated October 29, 1901.

Application filed September 26, 1899. Serial No. 731,536. (No model.)

To all whom it may concern:

Be it known that I, GEORGE R. PERRY, a citizen of the United States, residing in the city of New York, borough of Brooklyn, in the county 5 of Kings and State of New York, have invented certain new and useful Improvements in Disk or Coin Holders, of which the following is a specification sufficient to enable others skilled in the art to which the invention applies to make and use the same.

My invention relates to means for framing, suspending, or connecting coins, medals, and other similar disks which it would be undesirable or unlawful to perforate or otherwise 15 mutilate or deface.

The invention consists in certain special features of construction hereinafter more fully described and claimed.

In the accompanying drawings, Figure 1 is 20 an elevation of the holder without the disk or coin; Fig. 2, a section showing the coin or disk inserted, but not yet secured in place. Fig. 3 is a similar view showing the coin or disk secured in position. Fig. 4 is an elevation of a coin or disk to which my holder has 25 been applied; Fig. 5, a similar view to Fig. 4, showing a modified form of holder; Fig. 6, an edge view of the holder shown in Fig. 5; Fig. 7, a view of two holders connected together; Figs. 8 and 9, views showing other modifications in structure of the holder. Fig. 10 is a view showing two holders joined by a chain-link. Fig. 11 is a view illustrating diagrammatically the tightening of the band 30 upon a coin or disk.

C represents a coin, medal, or any other disk which it is desired to use as a pendant, part of a chain, a bangle, charm, or similar device for ornamentation or use.

40 B is a band, preferably though not necessarily of metal, adapted to encircle the coin or disk peripherally. This peripheral band B is formed with lateral flanges or projections b b', adapted to act as retaining-shoulders to confine the coin or disk against lateral displacement. In Figs. 1 to 7 and 10 and 45 11 these lateral projections are in the form of annular flanges, while in Figs. 8 and 9 an equivalent structure is shown, in which the shoulders are made in the form of lateral spurs b⁴ b⁵, projecting from the peripheral band B², said spurs being bent inward to con-

fine the coin or disk and performing the same function as the corresponding flanges b b' in the other figures. It is obvious in this connection that the essential feature consists in forming the peripheral band with lateral projections, which may be bent inward over the edge of the coin or disk after it has been placed within the band. Thus in Fig. 1 the 55 band B is shown with one flange b bent inward to receive and support the coin. Fig. 2 shows the same with the coin or disk C inserted within the rim and against the flange b, while Fig. 3 shows the other flange b' as having been turned over upon the edge of the coin or disk to lock it securely in position. The same result may be attained by the spurs b⁴ b⁵ in Figs. 8 and 9.

The peripheral band B is preferably made 70 to extend nearly but not completely around the circumference of the coin or disk, the ends b² b³ being united by a loop L, which answers the double function of an eye or link by which the coin or disk may be connected to another object, and of a take-up or tightening device by which the band may be firmly compressed against the periphery of the coin or disk. This latter result is accomplished by compressing or forcing the 75 sides of the link inward toward each other as far as the coin or disk will permit—that is to say, the slack is taken up and the band tightened around the periphery of the coin or disk by pinching the sides of the link toward each other. This operation is indicated symbolically in Fig. 11, in which the jaws of a pair of pincers are indicated as used for the purpose, although it is obvious 80 that other mechanical expedients may be employed with like result.

Another feature of my special construction consists in forming the ring with one or more open eyes or hooks E, by which it may be coupled to the link L' of another holder, as 95 indicated in Fig. 7, the end e being bent over to close the eye after a link L' and hook E have been coupled together, or the band B may be formed with two compressible links L, as in Fig. 9, and the bands connected by 100 ordinary or split-ring links R, as in Fig. 10.

My band or holder is designed as an article of manufacture which may be readily and conveniently applied to coins or disks of a

given size, the operation of turning the retaining-shoulders being comparatively simple and easy and requiring no special tools or appliances.

- 5 The device is especially adapted for use in connection with coins, which may not lawfully be perforated or otherwise mutilated or defaced, but which are much desired for use as watch-charms, pendants, bangles, &c.
- 10 The holder being made in sizes to correspond with the different denominations of coin, the latter can be so utilized whenever desired without the aid of a jeweler or skilled workman.
- 15 What I claim as my invention, and desire to secure by Letters Patent, is—
1. A disk or coin holder consisting of an annular band the opposed ends of which do not meet under normal conditions, adapted 20 to fit the disk or coin peripherally for the greater portion of its circumference and formed with laterally-projecting shoulders for confining both sides of the disk or coin, said band being also formed with a loop con-

necting its adjoining ends, which loop is capable of compression for the purpose of tightening the band upon the periphery of the disk or coin and is also adapted for use as a means of connecting the device with other objects, substantially in the manner 30 and for the purpose described.

2. A disk or coin holder consisting of an annular band the opposed ends of which do not meet under normal conditions, adapted to fit the disk or coin peripherally for the 35 greater portion of its circumference and formed with laterally-projecting shoulders for confining both sides of the disk or coin, said band being also formed with a compressible loop connecting the adjoining ends of the 40 band, and with a compressible hook for connecting the device to other objects, substantially in the manner and for the purpose described.
